UNITED STATES PATENT OFFICE

2,520,279

KNIFE SHARPENER

John Gallo, Medford, Mass.

Application May 16, 1946, Serial No. 670,099

1 Claim. (Cl. 76—87)

1

This invention relates to knife sharpeners of the type which employ partly overlapping steel disks between which the knife is drawn.

One object of the present invention is to provide a sharpener of this type wherein knives having their edges beveled on one side only may be sharpened, the metal being removed from the knife only on the beveled side.

A further object of the invention is to provide a sharpener in the use of which the metal of the knife is removed at one time from one face only, the other face being supported and rolled adjacent to the edge.

Still another object is to reduce the cost of manufacture of sharpeners of this type by requiring grinding of only one of the steel disks, this grinding being a costly operation.

Another object, where the disks are positioned on the same side of the support, is to provide means for limiting the lateral motion of the intermediate disk which will not require additional accuracy in the disk mountings.

For a complete understanding of this invention, reference may be had to the accompanying drawings in which

Figures 1, 2 and 3 are rear, end, and front elevations, respectively, of a sharpener embodying the invention.

Figure 4 is a sectional view to a larger scale on line 4—4 of Figure 1.

Figures 5 and 6 are diagrammatic views illustrating the sharpening actions of the several disks.

Figure 7 is a view somewhat similar to Figure 4, but showing a modification.

Referring first to Figures 1, 2 and 3 the sharpener comprises an angular plate support 1 having flanges 2 and 3 arranged at an obtuse angle to each other. The flange 2 is shown as provided with a pair of spaced perforations 4 for receiving fasteners (not shown) by which the sharpener may be mounted on any suitable support such as a handle member or a table top, or the like. The flange 3 carries three disks 6, 7 and 8. Each of these disks is shown as journaled on a rivet 9 and outwardly of each of the disks and between it and the adjacent end of the rivet is positioned a retaining washer 10. The central disk 7 is hardened and ground around its periphery at 11 to form with its side faces the sharp edges 12, and this center disk 7 is shown as positioned on the outside face of the flange 3. The side disks 6 and 8 are shown as arranged on the inner face of the flange 3. These side disks are not ground to present cutting edges, but instead may be circular

2

punchings, which, as they come from the stock, are formed with a rounded edge, as at 15. These rounded edges are presented to face the center disk 7. While these disks are not ground, they are preferably hardened so that the hard rounded edges 15 act to roll against the edge portion of a knife blade which is being drawn between the disks 6 and 7 or 7 and 8 where they overlap and remove or turn rough edge portions or burrs toward the opposite face of the knife for removal by the central disk. Such a punching is somewhat rough on its periphery, but this is not detrimental, it being important, however, for best results that these disks be hardened.

15 The effect of this arrangement is illustrated in Figures 5 and 6. Referring to Figure 5, the rounded disk 6 rolls against the knife edge on one side while the center disk 7 cuts the metal away on the other side. As shown, the sharpening is 20 all done on the right hand edge of the knife blade as viewed in the direction of Figure 5, the knife being drawn forwardly between the disks 7 and 6. When the knife is drawn between the disks 7 and 8, however, the cutting is done by the ground 25 disk 7 on the left hand face of the knife blade, while the disk 8 serves to roll the edge portion on the opposite face of the blade. From this it will be seen that if a knife having a bevel on one face only, as, for example, on the right hand face 30 as viewed in Figure 5, the knife will be drawn between the disks 6 and 7, while if the bevel of the edge is on the left, the knife will be drawn between the disks 7 and 8, as shown in Figure 6.

Where it is desired to sharpen the knife by removing stock from both sides, the knife is drawn first between the center disk 7 and one of the side disks and then between the center disk and the other side disk.

This arrangement makes possible the proper 40 sharpening of knife blades beveled on one face only, although it permits sharpening of knife blades beveled on both faces where this is desired. Also, since it is necessary to grind only one of the three disks, this being the center disk 7, and this 45 operation is relatively expensive, the cost of the sharpener is reduced from that of constructions where all of the disks are ground as well as hardened.

While as shown the center and side disks are 50 positioned on opposite faces of the flange 3, it being found desirable to separate the disks axially, nevertheless the same principle of operation may be performed where all the disks are carried on the same side of the support as shown in Figure 7. Where the disks are so arranged, the

center disk **1a** may be positioned between the washers **10** which are of less diameter than and are journaled substantially coaxially with the side disks on the side disk rivets, as shown. All the disks are loosely journaled on the rivets and the rivets are loosely set in the support, this looseness requiring no great accuracy in making or assembling the parts so that quantity production is easy and cheap, and it permits self-adjustment and rotation of the disks to present various portions from time to time into operative relation to the knife blade thus to distribute the wear. Since the central disk is spaced from the support with this construction, it might have undue play were it not for the washers **10** against one or the other of which it may be pressed by pressure exerted by the knife blade inserted between the center disk and the opposite side disk. These washers **10** then serve as stops with one or the other of which the central disk may engage and since this contact is with the edge of the center disk, it has no detrimental effect on its cutting edge. These washers **10** may be formed as punchings or burrs similar to the side disks **6** and **8**. This arrangement of disks and washers may be used, if desired, where all of the disks are ground and thus have cutting edges.

In operation the knife is preferably drawn from the back face of the flange **3** toward the forward face, and in a direction substantially parallel to the base flange **2**. This provides a shearing cut on the knife blade by the center disk **1**.

From the foregoing description of an embodiment of this invention, it should be evident to

those skilled in the art that various changes and modifications might be made without departing from its spirit or scope.

I claim:

5 A device of the class described, comprising a support, a center disk and two side disks loosely journaled to said support in partly overlapping relation on either side of said center disk, said center disk being hardened and having a ground 10 periphery presenting cutting edges with its side faces, and washers journaled coaxial with said side disks in the plane of said central disk and forming stops with one or the other of which said central disk may engage to limit the lateral 15 motion of said central disk by pressure of a knife blade inserted between said central disk and the opposite side disk.

JOHN GALLO.
